ENGINE CONTROL

Karl W. S. Ostling, Los Angeles, Calif., assignor
to California Machinery & Supply Co., Ltd., Los
Angeles, Calif., a corporation of Delaware

Application February 15, 1938, Serial No. 190,624

14 Claims. (Cl. 123—103)

This invention relates generally to apparatus for controlling the operation of internal combustion engines, and has to do specifically, in certain of its aspects, with combined deceleration and governor controls, with or without the added feature of manifold scavenging, and in other of its aspects with improvements in the individual controls. With respect to the general combination of controls, the invention provides various improvements over the system described in Vanderpoel Patent No. 2,107,314, issued February 8, 1938, on Means for automatically controlling flow of fuel mixture to internal combustion engines.

One of my principal objects is to provide an improved arrangement of governor and deceleration controls attached to a common controlled suction passage valve, so as to be independently operable in their valve control. In the present system, these controls are applied to an auxiliary valve positioned in the suction passage at the outlet side of the throttle, although in my copending application, jointly with A. G. H. Vanderpoel, on Engine deceleration and governor control, Ser. No. 191,684, filed Feb. 21, 1938, I show combination governor and deceleration controls applied to the throttle valve itself. The general purpose of the governor is to limit maximum engine speed during normal operation at open throttle. The deceleration control, on the other hand, operates independently of the governor to completely close the suction passage, and thereby to cut off fuel delivery to the engine, at times when the engine is operating at closed throttle under sub-normal load and at above idling speed. Such condition occurs when the engine is operating under momentum at closed throttle, as when the engine is being driven by a vehicle. In addition to the combination of governor and deceleration controls, the present system provides for the admission of scavenging gas to the manifold beyond the auxiliary valve during engine operation under momentum.

A further object of the invention is to provide a deceleration control device which is itself controllable to cause the auxiliary valve to open as the throttle is opened, in accordance with pressure changes in the suction passage between the throttle and auxiliary valve. The invention provides additional improvements with respect to deceleration controls involving the use of a suction passage pressure responsive pilot valve, that overcome certain objectionable characteristics of valve action experienced in other devices.

The invention includes a number of features and improvements in addition to those referred

to above, but all will be understood to better advantage without necessity for further preliminary discussion, from the following detailed description of the invention as embodied in certain of its typical and illustrative forms. 5 Throughout the description reference is had to the accompanying drawings, in which:

Fig. 1 is a transverse view showing the governor, deceleration control, and scavenging air valve mechanisms in horizontal section; 10

Fig. 2 is a vertical section on line 2—2 of Fig. 1;

Fig. 3 is a section on line 3—3 of Fig. 2;

Fig. 4 is a sectional view showing a variational form of relief valve; 15

Fig. 5 is a section on line 5—5 of Fig. 4;

Fig. 6 shows a second variational form of relief valve; and

Figs. 7 and 8 are diagrammatic views illustrating relative positions of the throttle and auxiliary valves under certain conditions of operation. 20

Referring first to Figs. 2 and 3, the suction passage, generally indicated at 10, comprises an upper section 11 which may be the lower part of a suitable down draft type carburetor. The lower section of the suction passage is formed by a body 12 having suitable means such as flanges 13, Fig. 2, for attachment to the engine intake manifold, not shown. Suction passage section 11 contains the usual throttle valve 14 carried on shaft 15 that is operated in the usual manner by suitable attachment to the throttle arm 16. As will be understood, the throttle 14 controls the flow of combustible fuel and air mixture from the carburetor to the engine, specific showing of the carburetor and idling fuel passage being omitted since they are unnecessary for full understanding of the invention. For reference purposes, suction passage at 10a above the throttle may be regarded as the inlet portion, and the passage at 10b below the later described auxiliary 40 valve as the outlet portion.

The auxiliary valve 17, which conveniently may be of the simple butterfly type, is carried on shaft 18 journaled in roller bearings 19 within section 12 of the suction passage at a suitable distance below the throttle 14. As best illustrated in Fig. 1, operation of the auxiliary valve 17 is controlled by a governor device, generally indicated at 20, connected to one end of the valve shaft 18, and by a deceleration control device, generally indicated at 21, applied to the opposite end of the shaft. Under certain conditions of engine operation, scavenging air is admitted to the suction passage at the outlet side of the auxiliary valve, under control of a piston operated air valve as- 55

sembly denoted at 22. It may be stated at this point that the function of the governor 20 is to control the position of the auxiliary valve independently of the throttle to limit engine speed at open throttle positions, while the function of the decelerating control 21 is to control, independently of the governor and throttle, the auxiliary valve to substantially completely close the suction passage when the throttle is in its closed (idling) position and the engine is operating under momentum. The function of the valve assembly 22 is to admit scavenging air to the manifold under the condition last named, i. e., when the engine is operating under momentum with the throttle closed. It is to be understood that in certain of its aspects, the invention is not to be regarded as limited to the use of a governor, deceleration control or air admission valve of any specific constructions, although the types and forms illustrated are preferred.

Referring to Fig. 1, the governor 20 comprises an elongated body 23 suitably attached to the block 12, one end 23a of the body being closed by cover plate 24 and forming a housing for the governor connected end 18a of the valve shaft, the opposite end 23b of the body containing a liner 25 that forms the governor piston cylinder. The outer end of the cylindric portion of the body is closed by threaded plug 26 carrying a removable cap 27. Piston 28 constitutes a pressure responsive element movable in accordance with pressure changes in the suction passage at the outlet side of the auxiliary valve, which pressure changes are communicated to the cylinder chamber 29 by way of opening 30 below valve 17 in closed position, see Fig. 3, passages 31 and 32, and a calibrated orifice 33. As viewed in Fig. 3, opening 30 lies at the near side of the suction passage, but is shown in dotted lines to illustrate its position below the valve 17.

The governor piston 28 has a lost motion connection with the valve shaft 18, by way of rod 34 pivoted to the bifurcated shaft arm 35. Head 34a on the outer end of the rod is received within a bushing 36 threaded into the piston and seating against a lock washer 36a, the seat portion 36b of the bushing being engageable with the head 34a to rotate shaft 18 in a valve closing direction, and the head 34a being movable away from the seat 36b to permit further closing of the auxiliary valve beyond that effected by the governor.

Movement of piston 28 in response to suction communicated to chamber 29 is yieldably resisted by a comparatively light coil spring 38 confined between the piston and plug 26. Toward the end of its valve closing travel, movement of the piston is also resisted by a comparatively strong spring 39 placed between an adjustment screw 40 and the head 41 of a guide pin 42 movable longitudinally within a bore 43 in the screw 40. At open throttle positions with the engine running at less than the maximum speed which the governor is set to maintain, piston 28 is moved by coil spring 38 to substantially the position shown, in which the piston is disengaged from the stop pin. As the engine speed tends to increase beyond the limit which the governor is set to maintain, suction communicated to the piston chamber 29 through passages 31, 32 and orifice 33, moves the piston to bring seat 36b into engagement with the rod head 34a, and then to rotate shaft 18 in a valve closing direction. As the piston approaches its limit of travel, it engages the stop pin head 41 and slightly compresses the relatively stiff spring

39 to the extent that the combined spring resistance arrests further travel of the piston.

The limit of piston travel in valve closing direction, and therefore the closed position of the valve and the governed engine speed, are determined by the position of the stop pin 42 and are controllable by adjusting screw 40 to vary the point at which the piston will come into engagement with head 41 of the stop pin. When the engine decelerates below its maximum governed speed, the pressure in chamber 29 is increased, permitting spring 38 to return the piston to its starting position. The auxiliary valve is movable to fully closed position under control of the decelerating device 21, as will presently appear, by reason of the lost motion connection between rod 34 and the governor piston.

The decelerating control and air valve assemblies are contained within a body 45 suitably attached to the side of block 12 opposite the governor. A chamber 46, closed by cover plate 47, receives the projecting end 18b of the valve shaft. The deceleration control 21 comprises a piston 48 within a cylinder formed by liner 49 inserted within a cylindrical bore in the body, the outer end 45a of which is closed by a plate 50 attached by screws 51 to the body flanges. Rod 52 having a ball and socket connection at 53 with the piston 48, is pivotally connected at 54 with an arm 55 carried on the valve shaft 18. Thus movement of the piston toward and away from the inner end of the cylinder operates respectively to open and close the valve 17. Valve closing travel of the piston is resisted by coil spring 56 confined between the piston and the cover plate 50, as illustrated.

Operation of the piston 48 under the influence of suction passage pressure is controlled by a pilot valve mechanism, generally indicated at 57, comprising a valve 58 normally closing passage 59 extending centrally through the cover plate 50, the valve stem 60 being confined within a tubular guide 61 formed integrally with the cover plate. Normally the valve is held in seated position by coil spring 62 bearing against a seat 63 supported by screw 64 extending through the spring housing 65, the screw being adjustable to regulate the spring resistance to opening of the valve. The piston chamber 66 is communicable under control of the valve 58, with the suction passage outlet 10b beyond the auxiliary valve 17, by way of passage 67 and the spring chamber 68. Spring 56 normally maintains the piston 48 in a position to the left of that illustrated, holding the auxiliary valve 17 open. At times when the throttle 14 is closed and the engine is operating under momentum, the depression communicated through passage 67 to the pilot valve chamber 68, causes the valve 58 to open against the resistance of spring 62, and to communicate the suction passage depression to chamber 66. Piston 48 thereupon moves against the resistance of spring 56 to the point of completely closing the auxiliary valve 17, it being understood that atmospheric pressure exists in the body chamber 46, as in chamber 70 at the inner end of the governor cylinder.

Return movement of piston 48 in a valve opening direction is controlled by a relief valve generally indicated at 71, see Figs. 2 and 3, the operation of which is controlled in accordance with the pressure existing in the suction passage between valves 14 and 17. Valve 71 comprises a cylindric body 72 having a lower tubular pin end 73 threaded into a boss 74 on top of body section 45 of the apparatus. The relief valve

body 72 is closed by cap 75 having a vent opening 76. Body 72 contains a piston 77 which carries a needle valve 78 that controls communication between the suction passage and piston chamber 66. Such communication occurs by way of passage 79 leading from a port 79a between valves 14 and 17, annular groove 80, passages 81, chamber 82, passage 83 and passage 84 extending longitudinally within body 45, see Fig. 2, to port 85 leading into the piston chamber. Valve 78 is raised from seating position in which it closes the upper end of passage 83, by a coil spring 86. Valve 78 operates to close passage 83 and the communication between port 79a and the piston chamber 66, at times when both the throttle 14 and auxiliary valve 17 are closed. Although the latter is fully closed, ordinarily in practice it is impossible to maintain a perfect fit between the valve periphery of the suction passage bore, with the result that some leakage will occur past the valve 17 resulting in a comparatively slight depression, say in order of $\frac{1}{2}$ " of water, between the two valves 14 and 17. Spring 86 is sufficiently light that piston 77 is responsive to the comparatively slight depression communicated through passage 79, to seat the valve 78. The valve 78 will thus be closed whenever there is a depression inside the throttle equal to or greater than that specified. And thus valve 78 will be closed not only whenever the throttle is closed but also ordinarily during operation of the engine throughout the normal operating ranges.

As previously explained, the deceleration control piston 48 operates to close the auxiliary valve when the throttle is closed and the engine is operating under momentum. During this time, the relief valve device 71 closes direct communication between the piston chamber 66 and the suction passage between the valves 14 and 17. Upon subsequent opening movement of the throttle 14, however, the depression between the throttle and auxiliary valves is relieved, with the result that valve 78 opens to bleed air from the suction passage into the chamber 66, thus causing the piston 48 to immediately open the auxiliary valve under the influence of spring 56.

In Figs. 4 and 5 I show a variational form of relief valve, generally indicated at 88, similar in general function to the described relief valve 71, but differing in that the valve proper is controlled by a pressure responsive diaphragm that causes the valve to vent air from the atmosphere outside the suction passage into the decelerator piston chamber, instead of venting air into the chamber from the suction passage. In the device 88, a diaphragm 89 is clamped between body sections 90 and 91, the chamber 92 below the diaphragm being vented to the atmosphere through opening 93. The diaphragm carried valve 94 seats upwardly to close communication between passage 84 and bore 95 connecting with chamber 92. At closed positions of the throttle and auxiliary valves, the suction passage depression is communicated by way of opening 79a and passages 79 and 96, to chamber 97 above the diaphragm to seat the valve 94. As the throttle is opened, relieving the depression above the diaphragm, the valve opens by gravity, to bleed air through opening 93, passages 95 and 84 into the piston chamber 66.

Fig. 6 shows a further variational form of relief valve similar in all respects to the form illustrated in Figs. 4 and 5, except that a floating type valve actuating diaphragm is used. Here

the diaphragm 98 is in the form of a thin disk bodily movable vertically within the body and having a slight clearance at 99, in the order of a few thousandths of an inch, from the bore wall 100. The clearance is sufficiently small to render the disk 98 immediately responsive to suction communicated to the chamber 97 above, and to enable the disk to hold the valve 94 closed during the continuance of such suction.

Referring now to the air valve assembly 22, part 101 clamped between body wall 102 and a tubular inlet 103, is shaped as illustrated to form a cylinder 104 for the piston 105, a seat 106 for the valve 107, and a guide 108 for the valve stem 109 attached at 110 to the piston. The piston chamber 111 communicates by way of tube 112 with passage 113 leading to the suction passage at the outlet side of the auxiliary valve 17, as indicated by the dotted line port 113a in Fig. 3, the port being shown in dotted lines since actually it is positioned in the near side of the suction passage as viewed in Fig. 3. Opening movement of the valve 107 is yieldably resisted by coil spring 114 and is limited by engagement with a stop screw 115 carried by spider 116 against which the spring bears, the stop screw being adjustable to regulate the open position of the valve.

Valve 107 opens during engine operation under momentum with the throttle and auxiliary valves closed, to admit scavenging gas (air) to the suction passage beyond the auxiliary valve, for the purpose of scavenging the manifold of fuel that might otherwise accumulate or remain within the manifold during momentum operation. Valve 107 normally is held seated by spring 114, but when the auxiliary valve 17 is closed and the engine is operating under momentum, the depression communicated to the piston chamber 111 by way of passage 113 and tube 112, advances the piston toward the left, opening valve 107 and admitting scavenging air to the manifold. The inner end of the piston chamber may be vented through opening 118 to permit immediate movement of the piston in response to the suction passage pressure communicated thereto.

The operation of the apparatus as a whole may be understood more clearly by considering diagrammatic Figs. 7 and 8, together with the other views. Assume first the engine to be operating at wide open throttle with the speed tending to exceed the maximum speed which the governor 20 is set to maintain (by adjustment of screw 40) as previously explained. The high speed engine operation produces a depression that is communicated through opening 30 and passages 31 and 32 to the governor piston chamber 29, causing the piston to close the auxiliary valve to an intermediate position such as illustrated in Fig. 7, to reduce the engine speed to the predetermined maximum. It will be understood that during governed maximum speed operation as just described, the depression existing in the suction passage at the outlet side of the auxiliary valve is insufficient to unseat the pilot valve 58 and thereby cause the deceleration control piston to close the auxiliary valve beyond the intermediate closed position maintained by the governor. The valve seating pressure exerted by spring 62 can be overcome only by the suction passage pressure existing during momentum operation with the throttle closed. Likewise, a corresponding low suction passage pressure is required to unseat the air admission valve 107.

so that the latter remains closed until the deceleration control 21 comes into operation.

Assume now that the throttle 14 is closed to idling position, see Fig. 8, and that the engine is operating under momentum. The depression communicated to the pilot chamber 68 by way of passage 67, unseats valve 58, communicating the depression to chamber 66 and causing the piston 48 to fully close the auxiliary valve 17, as shown in Fig. 8. As illustrated in Fig. 1, the lost motion connection between the governor piston 28 and rod 34 permits the auxiliary valve to become fully closed without interference by and independently of the governor. At the same time, the corresponding depression communicated to the air valve piston chamber 111 causes atmospheric pressure at the opposite end of the piston 105 to unseat valve 107, admitting scavenging air to the suction passage through passage 113.

During momentum operation, the relief valve 78 is held closed by the depression communicated through passage 79. As soon as the throttle 14 is again opened, the relief valve opens to admit air to the deceleration control piston chamber 66, causing the auxiliary valve to be immediately opened by spring 56. Simultaneously with the resultant increase in pressure in the suction passage outlet, spring 114 seats valve 107 to cut off the admission of scavenging air to the manifold, and spring 62 seats the pilot valve 58 if it has not been already seated by the provision herein-after explained. As soon as the auxiliary valve 17 opens the depression communicated to port 79a will again close the relief valve 78.

In connection with the operation of the deceleration control 21, it has been observed that where maintenance of valve closing depression within the piston chamber is exclusively under control of the pilot valve, the latter at times has a tendency to flutter or intermittently unseat in maintaining that depression. Also it has been observed, particularly in the operation of other forms of pilot valve mechanisms, that the valve action is influenced by heat from the engine. In accordance with the invention, we stabilize the operation of the pilot valve 58, and cause it to remain seated after initially opening to cause piston 48 to sufficiently close the auxiliary valve, by providing a port 120 that maintains a constant communication between passage 67 and the piston chamber 66. Port 120 is sufficiently restricted that upon rapid closing of the throttle during momentum operation of the engine, the depression communicated to passage 67 will cause the pilot valve 58 to unseat. However, after piston 48 is moved to its valve closing position, the constant communication of suction to the piston chamber through port 120 maintains the piston in that position, permitting the pilot valve to move to and remain seated.

In order that during normal operation piston 48 and the auxiliary valve 17 will remain unaffected by suction communicated to chamber 66 through port 120, I provide a calibrated orifice 121 in the wall of the piston chamber, see Fig. 2, which normally vents the chamber to the atmosphere and at such times relieves any suction in the chamber to the extent that spring 56 will maintain the auxiliary valve in open position. Orifice 121 however is closed by the piston at the end of its valve closing travel to seal the chamber so that the full depression communicated to the chamber will be effective for operation of the piston.

I claim:

1. In combination with an internal combustion engine, a carburetor and a suction passage connecting the carburetor with the engine, a throttle valve in said passage, an auxiliary valve in the passage at the engine side of the throttle, means actuated by virtue of engine operation under subnormal load at above idling speed to fully close said auxiliary valve, and means responsive to pressure in said suction passage between the throttle and auxiliary valves for causing the auxiliary valve to open from fully closed position.

2. In combination with an internal combustion engine, a carburetor and a suction passage connecting the carburetor with the engine, a throttle valve in said passage, an auxiliary valve in the passage at the engine side of the throttle, means comprising a pressure responsive member operable by virtue of abnormally low suction passage pressure at the engine side of the auxiliary valve to fully close the latter, and means responsive to suction passage pressure between the throttle and auxiliary valves for supplying air to said suction responsive member to cause the auxiliary valve to open from fully closed position.

3. In combination with an internal combustion engine, a carburetor, and a suction passage therebetween having a control throttle; an auxiliary valve in the suction passage, means actuated by virtue of depression in the suction passage greater than normal idling with the throttle in idling position, to fully close said auxiliary valve, said last mentioned means embodying a depression actuated element acting directly on the valve to close it, means for applying depression to said element only when the depression in the suction passage is greater than normal idling with the throttle in idling position, and means for relieving the depression applied to said element by virtue of pressure increase in the suction passage between said throttle and the auxiliary valve as the throttle is opened.

4. In engine fuel feeding apparatus comprising a suction passage having an inlet and an outlet, a throttle in said passage, and an auxiliary valve in the passage at the outlet side of the throttle; means forming a chamber communicable with said suction passage at the outlet side of the auxiliary valve, a pressure responsive member in said chamber connected to said auxiliary valve, a pilot valve device operable to communicate the outlet suction passage pressure to said chamber to cause said pressure responsive member to fully close the auxiliary valve when the throttle is closed and the engine is operating under momentum, a relief valve normally closing an air passage communicating with said chamber independently of said pilot valve device, and means responsive to the suction passage pressure between said throttle and auxiliary valve for opening the relief valve to admit air to said chamber to cause the auxiliary valve to open when the throttle is opened.

5. In engine fuel feeding apparatus comprising a suction passage having an inlet and an outlet, a valve in said suction passage, means forming a chamber communicable with the suction passage at the outlet side of the valve, a pressure responsive member in said chamber connected to said valve, a normally closed pilot valve operable to communicate the outlet suction passage pressure to said chamber to cause said pressure responsive member to close the suction passage valve, and means providing an open communication between said chamber and suction pas-

sage outlet independently of said pilot valve, when said pressure responsive member is positioned to close the suction passage valve.

6. In engine fuel feeding apparatus comprising a suction passage having an inlet and an outlet, a valve in said suction passage, means forming a chamber communicable with the suction passage at the outlet side of the valve, a pressure responsive member in said chamber connected to said valve, a normally closed pilot valve operable to communicate the outlet suction passage pressure to said chamber to cause said pressure responsive member to close the suction passage valve, and means providing an open communication between said chamber and suction passage outlet independently of said pilot valve, when said pressure responsive member is positioned to close the suction passage valve, the last mentioned means comprising a passage opening into said chamber and in constant communication with the suction passage outlet.

7. In engine fuel feeding apparatus comprising a suction passage having an inlet and an outlet, a valve in said suction passage, means forming a chamber communicable with the suction passage at the outlet side of the valve, a pressure responsive member in said chamber connected to said valve, a normally closed pilot valve operable to communicate the outlet suction passage pressure to said chamber to cause said pressure responsive member to close the suction passage valve, means providing an open communication between said chamber and suction passage outlet independently of said pilot valve, when said pressure responsive member is positioned to close the suction passage valve, and an air admission port in the wall of said chamber, said port being closed by said pressure responsive member in its valve closing position.

8. In engine fuel feeding apparatus comprising a suction passage having an inlet and an outlet, a valve in said suction passage, means forming a chamber communicable with the suction passage at the outlet side of the valve, a pressure responsive member in said chamber connected to said valve, a normally closed pilot valve operable to communicate the outlet suction passage pressure to said chamber to cause said pressure responsive member to close the suction passage valve, means providing an open communication between said chamber and suction passage outlet independently of said pilot valve, when said pressure responsive member is positioned to close the suction passage valve, the last mentioned means comprising a passage opening into said chamber and in constant communication with the suction passage outlet, and an air admission port in the wall of said chamber, said port being closed by said pressure responsive member in its valve closing position.

9. In combination with an internal combustion engine, a carburetor and a suction passage connecting the carburetor with the engine, a throttle valve in said passage, an auxiliary valve in said passage at the engine side of the throttle, means comprising a pressure responsive member adapted to close and open the auxiliary valve, control means actuated by abnormally low suction passage pressure to apply pressure to the valve operating member to close the auxiliary valve, and another control means actuated by suction passage pressure between the two valves adapted to apply pressure to the valve operating member to open the auxiliary valve.

10. In engine fuel feeding apparatus compris-

ing a suction passage having an inlet and an outlet, a valve in said suction passage, means forming a chamber communicable with the suction passage at the outlet side of the valve, a pressure responsive member in said chamber connected to said valve, a normally closed pilot valve means exposed on one face to the pressure existent in said chamber and on an opposite face to the pressure existent in the suction passage outlet and operable by difference between said pressures to communicate the suction passage outlet pressure to said chamber when said last named pressure is abnormally low, to cause the pressure responsive member to close said valve, and means for relieving the low pressure existent in said chamber.

11. In engine fuel feeding apparatus comprising a suction passage having an inlet and an outlet, a valve in said suction passage, means forming a chamber communicable with the suction passage at the outlet side of the valve, a pressure responsive member in said chamber connected to said valve, a normally closed pilot valve means exposed on one face to the pressure existent in said chamber and on an opposite face to the pressure existent in the suction passage outlet and operable by difference between said pressures to communicate the suction passage outlet pressure to said chamber when said last named pressure is abnormally low, to cause the pressure responsive member to close said valve, means independent of said pilot valve means and acting to apply the suction passage outlet pressure to said chamber when the pressure responsive member is positioned to close the suction passage valve, and means for relieving the low pressure existent in said chamber.

12. In engine fuel feeding apparatus comprising a suction passage having an inlet and an outlet, a valve in said suction passage, means forming a chamber communicable with the suction passage at the outlet side of the valve, a pressure responsive member in said chamber connected to said valve, said chamber having a port in its wall, an outwardly opening pilot valve seated in said port, means applying to the outer face of said pilot valve the pressure existent in the suction passage outlet, yielding means opposing opening movement of the pilot valve, passage means independent of said pilot valve acting to apply the suction passage pressure to said chamber when the pressure responsive member is positioned to close the suction passage valve, and means for relieving low pressure existent in said chamber.

13. In engine fuel feeding apparatus comprising a suction passage having an inlet and an outlet, a throttle in said passage, and an auxiliary valve in the passage at the outlet side of the throttle; means forming a chamber communicable with the suction passage outlet, a pressure responsive member in said chamber connected to the auxiliary valve, a normally closed pilot valve means exposed on one face to the pressure existent in said chamber and on an opposite face to the pressure existent in the suction passage and operable by difference between said pressures to communicate the suction passage outlet pressure to said chamber when said last mentioned pressure is abnormally low, to cause the pressure responsive member to close said valve, a relief valve normally closing an air passage communicating with said chamber independently of the pilot valve means, and means responsive to the suction passage pressure between the throttle and

auxiliary valve for opening the relief valve to admit air to said chamber to cause the auxiliary valve to open when the throttle is opened.

14. In engine fuel feeding apparatus comprising a suction passage having an inlet and an outlet, a throttle in said passage, and an auxiliary valve in the passage at the outlet side of the throttle; means forming a chamber communicable with the suction passage outlet, a pressure responsive member in said chamber connected to the auxiliary valve, a normally closed pilot valve means exposed on one face to the pressure existent in said chamber and on an opposite face to the pressure existent in the suction passage and operable by difference between said pressures to communicate the suction passage outlet pressure

to said chamber when said last mentioned pressure is abnormally low, to cause the pressure responsive member to close said valve, means independent of said pilot valve means and acting to apply the suction passage outlet pressure to said chamber when the pressure responsive member is positioned to close the suction passage valve, a relief valve normally closing an air passage communicating with said chamber independently of the pilot valve means, and means responsive to the suction passage pressure between the throttle and auxiliary valve for opening the relief valve to admit air to said chamber to cause the auxiliary valve to open when the throttle is opened.

KARL W. S. OSTLING.
